9 Claims. (Cl. 179—1)

Telephone systems are known which comprise a loud speaker and an amplified microphone permitting the subscribers to hear each other without taking the receiver to their ears and to speak directly into a microphone. It is also known to have relays in such systems which are controlled by the voice of the speaker, said relays controlling certain circuits of the system so that an acoustic coupling between the microphone and the loud speaker of the same station cannot take place. These vocally controlled relays are generally of the differential type so that the direction of the conversation depends not only on the intensity of the voice of the speakers but also on the noise which might arise in the places where the stations are located. It follows thereby that the direction of a conversation may be influenced by circumstances not depending on the will of the speakers.

Otherwise it is clear that the conversation between two stations equipped as described cannot take place with the same security and the same regularity as in telephonic conversations with apparatus provided with a micro-receiver. Indeed in these latter devices the danger of coupling does not exist and, as a directing relay is absent, the sensitivity of the device is greatly increased. It may be said that the two subscribers feel each other. It is not so in the loud-speaking and amplified microphone telephone systems where the subscribers having nothing to fix their attention, are inclined to answer either too early or too late. They can not follow the varieties of the conversation so well. They are less independent of what takes place around them because they have no receiver on the ears.

The present invention aims to provide a system where the various difficulties arising between the attendants of the two stations equipped with loud speaker and amplified microphone are lessened so much that the training which had to be acquired hitherto by long practice is automatically regulated. For this reason such systems may be left in the hands of any body and their use will be more extensive than has been the case up to the present.

The system according to the present invention is constructed in a manner that each station is equipped so that it can take the initiative of a conversation independently of the direction which might be given vocally. To this feature may be added that of a signalling system advising the attendants of the corresponding stations of the direction of the conversation and of the condition of the circuits if open or engaged. These signals enable the attendants:

(a) to concentrate their attention in the direction of the transmitter,
(b) to control the establishing of the connection at the moment of the call,

(c) to make sure that one of the attendants may speak so that the attendant at the other station may hear him,
(d) or, on the contrary, that one attendant should not speak because the attendant at the other station could not hear him,

(e) to advise them to speak sufficiently loud that they may be well understood,
(f) to advise them that the connection is actually interrupted when the conversation has ended.

The different named features may be combined in certain cases with each other or be partly lacking. The means for producing signals mentioned above may comprise any known form.

In the preferred form of the invention a certain number of stations having loud speakers and amplified microphones are grouped in an automatic central exchange comprising as is usual intercommunicating groups by means of which the attendants may be connected automatically with each other. In such a case the amplifying devices for the loud speakers as well as those for the microphones are connected to the central exchange where they belong to these intercommunicating groups. Also means may be provided for signalling from one station to the other in spite of the automatic operation, in the same manner as if the two stations were connected without the intermediary of a central exchange.

The annexed drawings show as examples three diagrams of systems according to the present invention.

Fig. 1 is a diagram showing two stations connected directly and provided with means for reciprocal intervention for directing the conversa- 40

Fig. 2 represents a similar arrangement having in addition a signalling system indicating various conditions.

Fig. 3 is a diagram of an automatic exchange where by means of call finders and of line selectors two stations may be connected, said stations being provided with signalling systems similar to those of Fig. 2.

With reference to Fig. 1 the stations I and II are each equipped with a loud speaker HP and a very sensitive microphone M. Besides they include a calling button α and an intervention button β . At each station there is a buzzer R. The outfit common to both stations comprises two 55

amplifiers AM_1 and AM_2 respectively two control relays C and C' for vocal control. The amplifiers are of a known system and shall not be described.

5 For establishing communication between station I and II the attendant at station I presses the button a and connects the buzzer with the positive pole of a battery and with the amplifiers through the contacts $A-1$ and $A-3$, said amplifiers transmitting the signal of the buzzer to the respective loud speaker. This signal passes to the microphone of station I and the produced current acts on the relay C .

10 A weakening resistance af preventing the acoustic coupling between the microphone and speaker of the same station is inserted in each of the loud speaker currents. If the attendant at station I speaks, the associated relay C is energized to open contact $C-1$, thus interrupting 15 the weakening circuit, and to open contact $C-2$ to break the circuit of the loud speaker at station I. Thus, the microphone of the hearer at station II is rendered ineffective.

20 This latter, therefore, must wait until the attendant at station I has stopped speaking before he may speak. It may be necessary, however, to interrupt before. This is done by means of button i at station II which allows the attendant at this station to switch on his transmitter into 25 the circuit of the loud speaker of station I. This is effected by closing a circuit in parallel with contact $C-2$ of the relay C and by the instant reestablishing of another weakening circuit including a resistance af , which is also connected 30 to said intervention button i .

35 When the conversation is to be ended the attendant at the station speaking presses the button d to reestablish the initial position of all parts. How this is done is not represented because it has nothing to do with the present invention.

40 With reference to Fig. 2 of the drawings, the stations I and II are likewise provided with a loud speaker HP , a microphone M , a calling button a , an intervention button i and a button d for ending the conversation. Each station possesses, in addition, the signalling lamps V (green), B (white), R (red) or V_1 , B_1 , R_1 respectively.

45 The two stations are shown directly connected but they could also be connected intermediately by an automatic device of known construction.

50 Weakening circuits, including resistances af , are provided according to need by the control relays C , or C' having each contacts 1, 2 and 3 and a buzzer R for calling.

55 When the operator at station I wants to establish connection with II he presses the button a and the amplifiers AM_1 and AM_2 are inserted 60 into the circuit. The buzzer R is operated, but placed after the amplifier. There is no relay C of the station I. By way of compensation, however, the noise produced in the loud speaker 65 HP of the station II is retransmitted by the microphone of station II. It results by this that relay C' is energized which at its contact 2 lights the green lamp V' of the called station II and the red lamp R of the calling station I. The operator at station I therefore has control of 70 his call and the called operator is invited to make himself known. If this has been done the relay C' will drop again and the red lamp of station I and the green lamp of station II will be extinguished. However the two white lamps B and 75

B' will be lit to prove that the connection has been established and that the line is free.

80 As soon as one of the operators begins to speak the relay C of station I or the relay C' of the station II is energized and whatever be the direction of the conversation it is the green lamp of the caller and the red lamp of the called which are lit alternatively.

85 The relay C or C' not only directs the conversation in one way or the other by cutting or re-establishing the circuit including the microphone of one of the operators and the loud speaker of the other operator, but also advises them of the direction of the conversation if the line is free.

90 In this form of the invention there is also an intervention button i by means of which one of the operators can shortcircuit the cut contact of his microphone and of the loud speaker of the other station in order to take the initiative of the conversation. It is not necessary to describe 95 the working of this button for it is the same as in the case of Fig. 1.

100 In Fig. 3 an intercommunicating group is represented between a central exchange and an auto-switch. This group is equipped with intervention and signalling devices described in the above. The station I is supposed to be the caller and the station II the called. It is clear that these characters may be reversed. The part III of the 105 drawings is the central exchange. The connection is established as follows:

110 The caller switches his station to the central exchange by pressing the calling button. When the connection has been made which is marked 115 optically the attendant connects himself with the desired station by means of his finger dial.

120 When the called station is free, it receives in its loud speaking set an auditory calling signal, which is also received by the caller, and which is automatically stopped after a certain time by a 125 relay energized through a current which is generated in the microphone of the called station by the sound waves emitted by the loud speaking set of the latter.

130 The emission of the call gives the called station 135 the priority of the conversation.

140 When the called person refuses the communication, because he is occupied or for any other reason, he sends an auditory signal in the loud speaking set of the caller by means of a refusing button, making use for instant of the calling circuits. Notified by this signal the caller cuts the 145 communication.

150 When the called operator accepts the communication, he announces himself. Then the unilateral communication, caller towards called person may continue.

155 If, during the conversation, one of the operators wants to interrupt the other and to take for a moment the priority of the conversation, he presses on an interfering button acting thus on the relays which invert the priority to his advantage.

160 Finally, if one of the operators, after having obtained the priority of the conversation wants to stabilize the communication in one direction only, he presses on his calling button. When he has to dictate a letter, to give a lecture or to transmit a fairly long communication, he thus avoids that at each temporary cessation in speaking, the relay system in the central exchange begins to work by taking off his priority of conversation said relay reestablishing the connection 165 as soon as he begins to speak again.

This operation does not, however, prevent the called operator from interrupting and thus removing the unilateral stabilization of the communication by pressing on the interfering button. The stabilization may be reestablished afterwards by the first operator as indicated above.

The exchange is provided with the ordinary apparatuses generally used in automatic telephony, such as a call finder CA, a line selector SU, an impulse sender EI and different relays belonging to each intercommunicating group.

The exchange comprises for each intercommunicating group symmetrically arranged an amplifier L_1 , L_2 , a rectifier valve L_2 and L_4 respectively, the transformers Tr_1 , Tr_2 and Tr_3 , Tr_4 respectively.

The intercommunicating group comprises the locking relays C, C', control relays H, H', interfering relays IN, IN', stabilizing relays F, F', feeding relays D, D', D'', a group relay I, coupling relays UU', impulse relays Y, call relays EE'; each station possesses a changeover relay for the signalling lamps S, S' and a line relay AA'. In the following description the denominations of the relays are not repeated and the contacts are designated by the letter of their relays having on the sides the number of said contact. In the diagram of Fig. 3, the contacts of the relays are only designated by their number, the letters of the relay being put in the margin on either side of the figure and an arrow beside each letter showing the direction in which the contacts of the corresponding relay can be found.

The working principle of the telephone exchange is as follows:

1. *Calling*.—The caller presses on the button a. In the exchange the light armature I of his line relay A as well as the armature of the impulse relay Y are energized.

Circuit: negative—connection VIII—contact I of the button a—connection VII—winding I of relay A—back contact A₄—back contact on the fuse carrier P_f—back contact B₃—winding I of relay Y—positive.

The contact A₂ prepares the circuit of test, contact Y₃ prepares the circuit of the group relay T—contact Y₁ energizes the call finder CA.

Circuit: negative—winding of the call finder CA—working contact Y₁—back contact B₂—back contact T₁—impulse sender EI—positive. The call finder rotates by going on the line of the caller, the armature of the relay T and the heavy armature II of the relay A are attracted.

Contact T₁ cuts off the call finder CA which stops on the line of the caller and energizes the relay B. Contact A₂ cuts the short-circuit of the line III—IV—contact A lights the red lamp on the calling station, thus advising the attendant that the central exchange is ready to be dialed.

Circuit: negative—contact A₁ connection IX—back contact S₂—red lamp R—connection X—positive.

When the relay B is energized, the contact B₁ prepares the dialing circuit—contact B₂ completes a holding circuit of relay B—contact B₃ cuts off the winding I of the relay Y. The contacts B₄ and B₆ connect the line III—IV on the relay Y—contact B₅ prepares a circuit of the relay T—B₈ prepares the circuit of the relay U and short-circuits the relay T which drops.

2. *Dialing*.—The caller dials. During the dialing his numeral dial short-circuits his loud speaker HP and makes the relay Y to act.

From the first impulse the contact Y₂ energizes

the relay J and the line selector SU. The latter makes a step at each impulse; the retarded relay J holds itself during the continuance of the impulse train.

When the relay J is energized, the contact J₁ cuts the short-circuit of the winding I of the relay Y—contact J₂ shunts the retarded winding of J and holds the relay U short-circuited.—Contact J₃ cuts the circuit of the relay T. The selector SU being out of its position of rest the contact SU₁ prepares the setting to rest of the selector SU. Contact SU₂ cuts off a short-circuit of the relay U and prepares a short-circuit of the winding I of relay Y.

When the dialing is finished, the relay J drops. Contact J₂ opens a short-circuit of the relay U which is energized, contact J₃ completes the circuit of the relay T.

The relay U being energized, the contacts U₁, U₃ separate the line III—IV from the relay Y and connect it to the transformer Tr 4, contact U₂ cuts the numbering circuit. The contact U₄ prepares a circuit of the relay NR; contact U₅ prepares a holding circuit of the relays D—D'—D''. The contact U₆ holds the relay B.

The relay Y drops.

3. (a) *The called station is busy*.—The relay T is short-circuited by the winding of small resistance of the relays T or the relay U of the group by which this station is busy. At the calling station the red lamp remains lit, no noise is perceived in the loud speaker HP. The caller is thus advised that the called station is not free.

(b) *The called station is free*.—At the dropping of the armature of the relay J the relay T of the group and the relay A' of the station are attracted.

Circuit: positive—B₅ working—J₃ back—winding II—I of relay T—arm C of the selector SU—winding II of relay A—connection VI—rest of button d¹—connection VIII—negative. If the relay T is energized the contact T₂ cuts the circuit of the calling relay E—the contact T₃ cuts a circuit of relay NR—the contact T₄ energizes the relays E—D—D'—D''—The contact T₅ cuts the dial circuit—The contact T₆ short-circuits the winding II of the relay T. The relays E—D—D'' are energized simultaneously but the hanging of E is sensibly quicker.

By energizing of relay E the contact E₁ short-circuits the relay of group G. The contact E₂ energizes a buzzer Ro in series with the windings I and II of the transformer Tr₁—the contact E₃ short-circuits the resistance RC placed between the windings of the transformer Tr₂—The contact E₄ closes a holding of the relay E—E₆ short-circuits the relay G₁ by a resistance.

The relays D—D'—D'' energized: The contacts D₁ and D₄ prepare a circuit of the calling microphone. The contacts D₃ and D₅ prepare a circuit of the called microphone.—The contact D₆ closes the circuit of the filament of the 4 triodes L₁ L₂ L₃ L₄—D'₁ prepares the receiving circuit of the called—The contact D'₃ prepares the circuit of the change over relay S' of the 65 signalling lamps of the station II—D'₁ prepares the receiving circuit of the called—The contact D'₂ cuts the energizing circuit of the calling relay E and maintains the relays E—D—D'—D''. The contact D'₄ prepares the circuit of the control relays H and H'—D'₅ completes the circuit of the change over relay of the lamps S of the calling station—The contacts S₁ and S₂ light up the white lamp, and the red lamp extinguishes.

The contacts D'₁ and D'₅ shall prevent that 75

during the rest of the intercommunication group numbers no current be inducted within the circuits of the loud speakers of the stations, currents which could produce a call.

5 49. *Call signal.*—When the contact B_2 is closed the called receives in his loud speaker an oscillation transmitted to him by the buzzer R_0 .

10 Circuit: positive—buzzer R_0 — E_2 working—primary winding I of the transformer $Tr\ 1$ —winding I of the induction coil—negative.

15 The oscillating current passing the winding I of the transformer $Tr\ 1$ is transmitted to the grid of the triode L_1 which produces a current of the same nature, but amplified in its anode circuit in which is included also the primary of the transformer $Tr\ 2$.

20 Circuit: negative common with the batteries (central and anodes), filament and space of filament and plate of the lamp L_1 —back contact of relay NR_1 —winding I of the transformer $Tr\ 2$ —contact C' —positive anodes.

25 The currents produced in the windings II and III of the transformer $Tr\ 2$ are transmitted to the called loud speaker by passing through the selector SU , arm d , e and the calling plate DA' .

30 The oscillations received by the called loud speaker are retransmitted by acoustic coupling to the central exchange by the microphone at the called station.

35 Circuit: winding II of the transformer $Tr\ 3$ working contact D_3 —arm a of the selector SU —connection II—working contact S_5 —back contact of button in' —microphone M' —connection I—arm b of SU —working contact D_5 —winding I of the transformer $Tr\ 3$ —condenser C ; the microphone being fed across the induction coil S_2 .

40 These microphonic currents are transmitted to the grid of the amplifying tube L_3 by the intermediate of the winding III of the transformer $Tr\ 3$, they produce currents of the same nature, but amplified in the anode circuit of L_3 in which is included the primary winding I of the transformer $Tr\ 4$.

45 Circuit: negative common to the batteries (central and anodes) filament and space of filament and plate of L_3 —back-contact NR_3 —winding I of the transformer $Tr\ 4$ —back contact C_1 —positive anode.

50 The currents of the winding I of the transformer 4 are transmitted, one part to the calling loud speaker by the intermediate of the windings II and III of the $Tr\ 4$. The caller is thus advised that the called has been called.

55 On the other part these currents arrive at the grid of the triode L_4 by the intermediate of the winding IV of the transformer $Tr\ 4$. They produce an amplified and detected current in the anode circuit of L_4 in which the winding of relay G' is found.

60 The intensity of the current increases until it suffices to cause the attracting of the armature of relay G' . At this moment the contact G'_3 relieves the short circuiting of the winding of the relay H' which is energized.

65 When the relay H' is energized the contact H'_1 cuts the calling relay E which drops and cuts the call, the contact H'_2 energizes the relay C' .

70 By energizing the relay C' the contact C'_1 cuts the anode circuit of the amplifying lamp L_1 . The contact C'_2 relieves the short-circuiting of a resistance RS' placed in the signalling circuit of the called. Therefrom results the dropping of the heavy armature I of his relay S' and the lighting of his green lamp by the working contact S'_2 and back contact S'_1 —The contact C'_3

short circuits the relay G — C'_4 short-circuits the receiver line III—IV of the called. The contact C'_5 cuts the signalling circuit of the caller. His relay S drops and causes the extinguishing of his lamp and the lighting of his red lamp by the back contact S_2 . The contact C'_6 short circuits the relay C' during the different commutations caused by the relay C' . The contact C'_8 short-circuits the weakening resistance RC' placed between II and III of the transformer 4 . 10

5 50. (a) *Being busy the called refuses the conversation*

Having received the call, the operator presses his refusing button d' . At the central exchange 15 his connecting relay A' and the group relay T drop. The calling relay E is again energized.

Circuit: positive— U_5 working— D''_2 working— T_2 back-winding of E , negative.

At the dropping of relay T the contact T_3 closes 20 the circuit of the relay NR which is energized.

Circuit: positive— D''_5 working— T_3 back— U_4 working—winding of NR —negative.

The relay E controls again the calling circuit. The relay NR reverses at its contacts NR_1 and NR_3 the anode circuits of the triodes L_1 and L_3 and the oscillating current produced by the buzzer R_0 and amplified by the triode L_1 will be received this time by the intermediate of the transformer $Tr\ 4$ by the loud speaker of the 30 caller.

Advised by this signal the caller presses his button d whereby the connection made will be cut off at the central exchange.

(b) *The called accepts the communication* 3

Having received the call, the operator makes himself known by the words "here station X". This answer is transmitted by his amplified microphone by L_3 , is received by the loud speaker of the caller and by the detecting tube L_4 which holds the relay G' by the circuits following in the explanation given for the working of the call.

When the called has answered he leaves the 4 speech to the caller. As the relay G' receives no more current it will drop, the control relay H' and the locking relay will drop retarded. The contact C'_1 reestablishes the anode circuit of L_1 . The contact C'_2 short-circuits the resistance RS' included in the signalling circuit of the called which will cause the energization of the heavy armature II of his change over relay of the lamps S' and will cause the lighting of the white lamp by the working contacts S'_1 and S'_2 .

The contact C'_3 short-circuits the relay G and the contact C'_4 short-circuits the receiver line III—IV of the called. The contact C'_5 closes again the signalling circuit of the caller which will cause the energizing of his relay S and will cause the lighting of the white lamp by the working contacts S_1 and S_2 . The contact C'_8 short-circuits the weakening resistance RE' placed between the windings II and III of the transformer $Tr\ 4$.

At this moment the white lamp at the two stations advises that the double connection (going and returning) has been established. The effect of the receiving is moderated by the resistances placed between 4 and 5 of the transformers $Tr\ 2$, $Tr\ 4$ and by the condensers shunted with the loud speakers by the working contacts S_3 . This effect is regulated slightly above the limit of priming.

6. *The caller speaks.*—By his microphone his conversation is transmitted to the transformer T_1 1, amplified by the triode L_1 , received by the called loud speaker, the detecting lamp L_1 and the relay G which is energized.

When this relay G is energized the contact G_1 blocks the relay G' by short circuiting the same. The contact G_3 short-circuits the control relay H which is energized. The contact H_1 energizes the locking relay C and light armature I of the stabilizing relay F .

The locking relay C being energized, the contact C_1 cuts the anode circuit of L_2 . Contact C_2 opens the circuit of the resistance RS included into the signalling circuit of the calling station, the result of which is to cause the dropping of the heavy armature II of its relay S and to cause the lighting of its green lamp by means of the working contact S_2 and the back contact S_1 . The contact C_4 short-circuits the receiving line of the caller. Contact C_5 cuts the signalling circuit of the called station whereupon the relay S' is dropped and its red lamp is lighted by the back contact S'_2 . The contact C_6 short-circuits the relay G during the process of commutation assured by the locking relay C . The contact C_8 short-circuits the weakening resistance RC connected between the windings II and III of the transformer T_2 .

The contact F_2 prepares the circuit of the control winding of the heavy armature II of the stabilizing relay F .

On this principle the communication may continue without limit. Each time that one of the interlocutors stops to speak the communication becomes bilateral (white lamp at the two stations), and the initiative of the conversation may be taken up by one or the other of the attendants.

7.—*Interfering.*—However if one of the two operators is leading the conversation, it may be useful that the other be able to interrupt him. In this case, the latter (the operator on the called station) presses once his button in' . His microphone is then cut out by the contact I and the interfering relay IN' is energized by the contact 2 of the button in' .

Circuit: positive—connection X —contact 2 of the button in' —connection J —arm f of selector SU —back contact C_2 —working contact C_5 —the relay IN' —negative.

The interfering relay IN' being energized, the contact IN'_1 cuts the circuit of the central relay H .—The contact IN'_2 cuts the circuit of the relay G . Contact IN'_3 cuts the retarded circuit of the relay H , so that the latter may drop rapidly. The contact IN'_5 completes a holding circuit of the relay IN' .

Circuit: positive—working contact B_5 —working contact IN'_5 —back contact H'_3 —winding of the relay IN' —negative.

The relay H being cut off, its contact H_1 opens the circuit of the locking relay C which drops. The contact C_1 completes the anode circuit of the amplifier L_2 . Contact C_4 opens the short-circuit of the loud speaker line of the caller. By this fact, the initiative of the conversation is given to the attendant at the called station. On the other hand, when the latter lets go the interfering button in' , his microphone circuit is completed again. The current impulse generated thereby energizes the relay G' . The contact G'_3 opens the short-circuit of the winding I of control relay H' , the armature of which is consequently attracted. The contact H'_2 energizes the locking relay C' which, by means of its contact C'_4 short-

circuits the loud speaker line of the attendant at the called station. The contact C'_1 opens the anode circuit of the amplifier L_1 , so that microphone currents of the station I are not transmitted to the loud speaker circuit of the called station. The caller loses his priority. The contact H'_3 cuts out the relay IN' which drops, its function being terminated.

The caller may, in his turn, interfere in the same way. This time it will be the relay IN 10 which to his advantage will play the part which the relay IN' has played to the advantage of the called station. The buttons in and in' shall also be used each time when there is noise in the room where the called interlocutor is staying. 15

8.—*Stabilizing the communication in one direction*

If one of the interlocutors having the initiative of the conversation wants to dictate a letter, to 20 lecture or to make a fairly long conversation, he may stabilize the communication in the direction in which he is speaking by pressing on his button a . He thus energizes the stabilizing relay F in the case of the caller, or the relay F' respectively for 25 the calling station.

Circuit: (for the caller) positive—connection X —contact 2 of the button a —connection IV —working contact A_3 —arm d of the call finder CA —working contact B_4 —working contact U_1 —winding III of the transformer T_2 —working contact F_2 —winding II of the relay F —negative. 30

The heavy armature II of the relay F being energized, the contact F_1 doubles the contact G_2 —contact F_3 holds the relay F . 35

Circuit: positive—working contact B_5 —back contact IN'_5 —working contact F_3 —winding II of the relay F —negative.

The attendant may then speak low or even stop speaking, the relay G drops again but the relay 40 H is held by the contact F_1 . The communication remains then stabilized in the direction from the speaker to the hearer. However, the hearer always retains the possibility of interrupting by pressing once the button in' . By this operation 45 the relay IN' is energized and the contact IN'_5 cuts the holding circuit of the relay F . Everything becomes normal again.

What I claim as new is:

1. A telephone system comprising a plurality of 50 stations, each including a transmitter and a loud-speaking receiver, a circuit including an amplifier connecting the transmitter at one station with the receiver at a second station, a second circuit including an amplifier connecting the transmitter 55 at the second station with the receiver at the first station, a relay, a relay-opened switch in each circuit, the relay in one circuit controlling the switch in the other circuit, whereby, upon energizing the relay in one circuit, the switch in the other circuit will be opened to break the last-recited circuit, a manually-controlled interrupting switch at the station including the transmitter of the first-recited circuit, a circuit including said interrupting switch and shunted across the switch in 60 said first-recited circuit, a second manually-controlled interrupting switch at the second station, and a circuit including said second interrupting switch and shunted across the switch in said second circuit. 65

2. A telephone system comprising a plurality of stations, each including a transmitter and a loud-speaking receiver, a circuit including an amplifier connecting the transmitter at one station with the receiver at a second station, a second circuit in- 75

cluding an amplifier connecting the transmitter at the second station with the receiver at the first station, a relay, a relay-opened switch in each circuit, the relay in one circuit controlling the switch in the other circuit, whereby, upon energizing the relay in one circuit, the switch in the other circuit will be opened to break the last-recited circuit, a circuit including a resistance and a switch shunted across each receiver, and means controlled by the relay in each of the receiver circuits upon energization of the respective relays for opening the switch to break the respective associated resistance containing circuit.

3. A telephone system comprising a plurality of stations, each including a transmitter and a loud-speaking receiver, a circuit including an amplifier connecting the transmitter at one station with the receiver at a second station, a second circuit including an amplifier connecting the transmitter at the second station with the receiver at the first station, a relay, a relay-opened switch in each circuit, the relay in one circuit controlling the switch in the other circuit, whereby, upon energizing the relay in one circuit, the switch in the other circuit will be opened to break the last-recited circuit, a circuit including a resistance and a switch shunted across each receiver, means controlled by the relay in each of the receiver circuits upon energization of the respective relays for opening the switch to break the respective associated resistance containing circuit, a manually-controlled interrupting switch at the station including the transmitter of the first-recited circuit, a circuit including said interrupting switch and shunted across the switch in said first-recited circuit, a second manually-controlled interrupting switch at the second station, a circuit including said second interrupting switch and shunted across the switch in said second circuit, and a circuit including a resistance associated with the interrupting switch at one station for shunting the receiver at the same station upon actuation of the interrupting switch.

4. A telephone system comprising a plurality of stations, each including a transmitter and a loud-speaking receiver, a circuit including an amplifier connecting the transmitter at one station with the receiver at a second station, a second circuit including an amplifier connecting the transmitter at the second station with the receiver at the first station, a relay, a relay-opened switch in each circuit, the relay in one circuit controlling the switch in the other circuit, whereby, upon energizing the relay in one circuit, the switch in the other circuit will be opened to break the last-recited circuit, a pair of signal lights of the same color, one at each station, a circuit connecting said lights in parallel, a two-way switch associated with each relay, a circuit serially including said two-way switches for energizing said parallel light circuit when both two-way switches are unaffected by the relays, a light of a second color and a light of a third color at each station, a circuit connecting the light of the second color at one station with the light of the third color at the other station, and means including said two-way relay-actuated switches for connecting said light circuits to cause the light of the second color to be lighted at the speaking station and the light of the third color to be lighted at the listening station during transmission.

5. A telephone system comprising a plurality of stations, each including a transmitter and a loud-speaking receiver, a circuit including an amplifier connecting the transmitter at one station with

the receiver at a second station, a second circuit including an amplifier connecting the transmitter at the second station with the receiver at the first station, a relay, a relay-opened switch in each circuit, the relay in one circuit controlling the switch in the other circuit, whereby, upon energizing the relay in one circuit, the switch in the other circuit will be opened to break the last-recited circuit, an interrupting switch at the station including the transmitter of the first-recited circuit, a circuit including said interrupting switch and shunted across the switch in said first-recited circuit, a second interrupting switch at the second station, a circuit including said second interrupting switch and shunted across the switch in said second circuit, a pair of signal lights of the same color, one at each station, a circuit connecting said lights in parallel, a two-way switch associated with each relay, a circuit serially including said two-way switches for energizing said parallel light circuit when both two-way switches are unaffected by the relays, a light of a second color and a light of a third color at each station, a circuit connecting the light of the second color at one station with the light of the third color at the other station, and means including said two-way relay-actuated switches for connecting said light circuits to cause the light of the second color to be lighted at the speaking station and the light of the third color to be lighted at the listening station during transmission.

6. A telephone system comprising a plurality of stations, each including a transmitter, a loud-speaking receiver and a station calling dial, a central exchange common to said stations, a circuit at said exchange for transmitting from the calling station to the called station, a second circuit at the exchange for transmitting from the called to the calling station, means at the exchange operable upon transmission over one circuit for preventing transmission over the other circuit, a call finder at the exchange for connecting said circuits to the calling station, means at the calling station and at the exchange for actuating said call finder, a line selector for connecting said circuits to the called station, means actuated by the dial at the calling station for operating said line selector, interrupting means at the exchange for blocking transmission over either of said circuits, and means at said stations and connected through said call finder and line selector to said interrupting means for controlling the latter.

7. A telephone system comprising a plurality of stations, each including a transmitter, a loud-speaking receiver and a station calling dial, a central exchange common to said stations, a circuit at said exchange for transmitting from the calling station to the called station, a second circuit at the exchange for transmitting from the called to the calling station, means at the exchange operable upon transmission over one circuit for preventing transmission over the other circuit, a call finder at the exchange for connecting said circuits to the calling station, means at the calling station and at the exchange for actuating said call finder, a line selector for connecting said circuits to the called station, means actuated by the dial at the calling station for operating said line selector, signal lamps at each of the stations of three different colors, means operable upon establishing a connection between the station for energizing lights of a first color at both stations, means operable upon transmission from the calling to the called station for ener-

gizing a light of a second color at the calling station and a light of a third color at the called station, and means operable upon transmission from the called to the calling station for energizing a light of the second color at the called station and a light of the third color at the calling station.

8. A telephone system comprising a plurality of stations, each including a transmitter, a loud-speaking receiver and a station calling dial, a central exchange common to said stations, a circuit at said exchange for transmitting from the calling station to the called station, a second circuit at the exchange for transmitting from the called to the calling station, means at the exchange operable upon transmission over one circuit for preventing transmission over the other circuit, a call finder at the exchange for connecting said circuits to the calling station, means at the calling station and at the exchange for actuating said call finder, a line selector for connecting said circuits to the called station, means actuated by the dial at the calling station for operating said line selector, a calling contactor at each station, and stabilizing means at the exchange under control of the calling contactors

for maintaining one of said transmission circuits blocked upon a pause in the transmission over the other circuit.

9. A telephone system comprising a plurality of stations, each including a transmitter, a loud-speaking receiver and a station calling dial, a central exchange common to said stations, a circuit at said exchange for transmitting from the calling station to the called station, a second circuit at the exchange for transmitting from the called to the calling station, means at the exchange operable upon transmission over one circuit for preventing transmission over the other circuit, a call finder at the exchange for connecting said circuits to the calling station, means at the calling station and at the exchange for actuating said call finder, a line selector for connecting said circuits to the called station, means actuated by the dial at the calling station for operating said line selector, a refusing contactor at each station, and means at the exchange controlled by the refusing contactor for causing a refusing signal to be transmitted from the called station to the calling station.
